UNITED STATES PATENT OFFICE.

THOMAS J. STEARNS, OF BOSTON, MASSACHUSETTS.

DESIGN FOR A CARPET.

SPECIFICATION forming part of Design No. 14,077, dated July 10, 1883.

Application filed May 31, 1883. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in accompanying photographic illustration.

The design is composed of the free-hand floral and foliage designs, arranged in bouquets or masses, and in detached sprays, and a finely-mottled groundwork, all as shown.

I claim—

The design for a carpet, substantially as shown and described.

In testimony whereof I have signed my name to this specification, in the presence of two subscribing witnesses, this 26th day of May, 1883.

THOMAS J. STEARNS.
